UNITED STATES PATENT OFFICE.

MAX BUCH, OF DETROIT, MICHIGAN, ASSIGNOR TO HENRY E. EDWARDS, OF JACKSON, MICHIGAN.

FOLDING TOP.

1,336,022.

Specification of Letters Patent.

Patented Apr. 6, 1920.

Application filed March 24, 1919. Serial No. 284,734.

To all whom it may concern:

Be it known that I, MAX BUCH, a citizen of Germany, and resident of Detroit, Michigan, have invented certain new and useful

5 Improvements in Folding Tops, of which the following is a specification.

My present invention relates to improvements in folding tops for motor vehicles, motor boats and the like.

10 One object of the invention is to provide a top frame which will be wholly supported by a single standard on each side in addition to the usual wind-shield connection, and in which all bows and links will be wholly connected from exterior view by the top covering.

Another object is to provide a top which may be projected from its folded position by the mere act of raising or pushing upward upon the main bow, which, by reason of its extending rearwardly from its pivot, is easily manipulated from the rear of the machine, thus avoiding any twisting strains on the top parts, such as occur with tops 25 which are operated from the side.

With these and other objects in view the invention includes the novel features of construction and arrangement of parts herein-after described, my said invention being defined by the appended claims.

My preferred embodiment of said invention is illustrated in the accompanying drawings, in which,

Figure 1 is a sectional elevation of the top 35 in extended position upon a motor vehicle body, only a portion of which latter is shown in outline for convenience of illustration.

Fig. 2 is a similar view with the extension parts folded back against the main bow.

40 Figs. 3, 3^a, 4, 5 and 6 are views of modifications.

The top being shown in elevation the bow arms, links and levers on one side only appear in the drawing, but it will be understood that they are duplicated on the opposite side, and where, in the subjoined description the singular is used as applying to one side it will be understood to apply to the opposite side also.

50 Referring by reference characters to this drawing the numeral 1 designates a vehicle body, 1^a the top covering material, and 2 the main bow standard which has its lower end pivotally connected to the body preferably by having a rearwardly curved portion 2^a

which is pivotally supported by a body iron or pin 3 secured in a suitable manner to the vehicle body.

The bow standard or arm 2 inclines rearwardly so as to lie in approximately the same position as the rear bow of the conventional type of top and it supports at its upper end the corresponding end of the bow 2^b, though obviously the bow may be made integral with the standard or arm where an all metal top is desired.

In the embodiment shown in Figs. 1 and 2 a pair of links or members 3 and 4 have their rear portions pivotally connected to the bow arm 2, one above the other, as indicated at 3^a and 4^a. The forward extremity of one of these links (3) is connected by a hinge joint 3^b of preferably the elbow or lock type to the rear end of a bow arm 5 carrying a bow 5^a, (integral or otherwise) which for convenience I term an extension bow arm. The forward extremity of the other link (4) is connected by a pivot indicated at 4^b to the bow arm 5 a suitable distance in advance of the pivot 3^b. One of the links (3) has pivotally connected therewith at 6^a the lower or rear end of a bow arm 6 (for convenience of designation called the intermediate bow arm) carrying a bow 6^a, and to this bow arm is pivotally connected at 7^a the rear end of a member 7, which, in the projected position of the top, extends diagonally across the bow arm 5 to which it is pivotally connected at 7^b.

To the forward end of this member is pivotally connected at 8^a the rear end of another extension bow arm which corresponds to the usual outrigger bow arm 8, and will be so designated hereinafter. A link or brace 9 has one end pivotally connected with the outrigger bow arm 8 at 9^a and the other end pivotally connected with the bow arm 5 at 9^b.

One of the links or members 3 or 4 is extended to form a top projecting lever, in the preferred embodiment shown in the drawing the lower member 3 being shown as having such extension, indicated at 3^x, and the end of the extension is connected by a flexible element 10, such as a strap or webbing, with the back of the body in any suitable manner, the end of the extension being preferably bent or turned at right angles to enter a loop 10^a on the strap.

The two extensions 3^x may be connected 110

by a single transverse bar forming a continuation of the angularly turned portions, and it will be observed that if the bow 2^b is pulled backwardly and downwardly a simultaneously upward push upon said transverse bar will cause the articulated joints to break downwardly without necessitating the operator going to the sides of the vehicle.

With a top constructed as above described 10 it will be readily seen that to project it from the folded position it is only necessary for the operator to push upwardly on the central portion of the bow 2^b so as to swing both bow standards 2 upwardly, carrying with 15 them the folded links or levers and bows. As soon as the straps or webs have been drawn taut further upward movement of the standards causes the links or levers 3 to rock about their points of pivotal connection 20 with the bow standards 2 and the top extension to be projected in a substantially horizontal direction.

In the form shown in Fig. 3 I have eliminated the forwardly inclined bow, and extended the member 7 to form, or shaped it to carry, as indicated at 7^x, the rearwardly inclined cover supporting bow X, the element 6^x in this instance comprising solely a link connecting member 7^x with the member 4.

In a similar manner I have extended the member 9 as shown at 9^x, or shaped it to carry the bow X', the member 5^x terminating at its forward end in its point of pivotal connection with arm 9^x.

In some instances, it may be found desirable to reduce the height of the rear curtain as in case of high tops and this may be readily accomplished by forming the part 40 connecting the extensions 3^x as a cover supporting bow shown at 3^y in Fig. 4, the top covering being continued beyond the bow 2^b as indicated at 1^b and having its terminal edge secured to the bow 3^y to which the upper edge of the back curtain 11 is secured.

Where constructional reasons render it desirable the lower and upper members 3 and 4 may be connected so that the strain of the straps 10 will be transmitted to both elements 3 and 4 by providing the one of the members with a short arm or bell crank extension 4^x connected by a link 12 with the extension of the other member as shown in Fig. 5. This enables the long portions of 55 said members which extend forward from their pivots to be made lighter than otherwise without danger of springing under the weight of the forward extension.

I have shown as a convenient embodiment 60 of my invention a four-bow top. It will be perfectly obvious, however, that it is adapted for a roadster or chummy roadster, which needs only a three-bow top by omitting the outrigger bow 8, the link 9 and the 65 forward portion of the link or lever 7, in

which event the extension bow 5 would constitute the outrigger bow, being in this event dropped down to a horizontal position by the lengthening of the link connection between the bow arm 5 and the bow arm 6. 70

A desirable form of three bow top may be secured by utilizing the structure shown in my U. S. Letters Patent 1,287,629, dated December 17, 1918 as shown in Fig. 6 by providing one set of links 19 supporting the 75 arms of the outrigger or extension bow with portions or extensions 19^x extending in rear of the points of pivotal connection between said links and the main bow, these extensions being connected by straps or webbing 80 10 with the body.

It will be seen that my improved top embodies but a single supporting standard or bow arm, which is well to the rear and out of the line of vision of the occupants of the 85 rear seat. Its position adapts it to have the back covering material brought around to and connected with the sides of the said supporting standard or bow arm, so as to conceal the latter from exterior view and 90 yet not interfere with the vision of the occupants of the rear seat, and as all of the extension members heretofore described are well above the lower edge of the top covering material my improved top presents a 95 construction in which all of the frame members are concealed from exterior view.

What I claim is:

1. In a vehicle top a main bow arm adapted for pivotal connection with a vehicle body and to normally extend upward in relation thereto, a pair of links pivotally connected at their rear ends to said main bow arm, one of said links having a lever extension, means for flexibly connecting 100 said lever extension with the vehicle body, a member having its rear end pivotally supported from the forward end of said links, a second member having its intermediate portion pivoted to the intermediate portion 105 of said first named member, an outrigger bow arm pivotally connected to the forward end of said second member, means connecting a portion of said second member in rear of its pivot to one of said links, and means connecting a portion of said first named member in front of its pivot with the outrigger bow arm. 110

2. In a vehicle top a main bow arm adapted for pivotal connection with a vehicle body, a pair of links pivotally connected at spaced points with said main bow arm, one of said links having a lever extension, means for flexibly connecting said lever extension with said body, a member 120 having its rear end pivotally supported from the forward end of said links and inclining upwardly and forwardly therefrom, a second member crossing said first member and pivoted thereto, an outrigger bow arm 125 130

pivots supported from the forward end of said second member, means connecting the forward portion of said first named member with the outrigger bow arm in advance of its pivot, and means connecting the rear portion of said second named member with one of said links.

3. In combination with a vehicle a main bow arm pivotally connected to the vehicle body at a substantial distance from the rear end thereof and inclining upwardly and rearwardly with its upper end substantially vertically above said rear end when the top is unfolded, a pair of links pivotally connected directly to said bow arm and projecting forwardly therefrom, one of said links having a lever extension, a flexible element connecting said lever extension with the rear end of the vehicle body, and an outrigger bow arm supported by said links.

4. The combination with a vehicle body, of a rearwardly and upwardly inclined main bow arm pivotally connected with the vehicle body and having its upper end lying substantially vertically above the rear end of said body, an extension bow arm, a link connecting said extension bow arm with the main bow arm, and having a lever extension, flexible means connecting said lever extension with the rear end of the vehicle body, an intermediate bow arm pivotally connected to said link, and a link connecting said intermediate bow arm with said extension bow arm.

5. The combination with a vehicle body, of a main bow arm pivotally connected therewith, an extension bow arm, a link connecting said extension bow arm and main bow arm and having a lever extension, flexible means connecting said lever extension with the vehicle body, an intermediate bow arm pivotally connected to said link, a member fulcrumed on said extension bow arm and having one end pivotally connected to said intermediate bow arm, an outrigger bow arm pivotally connected to the other end of said member, and a link connecting said outrigger bow arm with said extension bow arm.

6. The combination with a vehicle body, of a main rearwardly inclined bow arm

pivots connected therewith, an extension bow arm, a pair of links pivotally connected at their rear ends to said main bow arm, one above the other and at their forward ends to said extension bow arm, one in advance of the other, one of said links having an extension in rear of its point of pivotal connection to the main bow arm, a flexible element connecting said extension with the vehicle body, an intermediate bow arm pivotally connected with one of said links, a member fulcrumed on said extension bow arm, and having its rear end pivotally connected with said intermediate bow arm, an outrigger bow arm pivotally connected to the other end of said member and a link connecting the outrigger bow arm with said extension bow arm.

7. In a vehicle top, a main bow arm adapted to be pivotally connected to a vehicle body and to normally extend upwardly in relation thereto, an extension bow arm, a pair of links pivotally connected respectively to said main bow arm and said extension bow arm, an intermediate bow arm pivotally supported from one of said links, a member fulcrumed on said extension bow arm and having its rear end pivotally connected with said intermediate bow arm, and an outrigger bow arm pivotally connected to the forward end of said member.

8. In a vehicle top, a main bow arm adapted to be pivotally connected with a vehicle body, to normally extend upwardly and rearwardly in relation thereto, an extension bow arm, a pair of links pivotally connected at their rear ends to the main bow arm, one above the other, and at their forward ends to said extension bow arm, one in advance of the other, an intermediate bow arm pivotally connected to one of said links, a member fulcrumed on the extension bow arm and having its rear end pivotally connected with said intermediate bow arm, an outrigger bow arm pivotally connected to the other end of said member, and a link connecting the outrigger bow arm with said extension bow arm.

In testimony whereof, I affix my signature.

MAX BUCH.
